REPAIR LOCK

Lawrence B. Scott, Columbus, Ohio

Application May 17, 1943, Serial No. 487,371

2 Claims. (Cl. 189—36)

1

This invention relates to new and useful improvements in repair locks.

One object of the invention is to provide an improved cold flow lock, which is adapted for use in repairing and reinforcing cracked and fatigued castings, forgings and other metallic members, and which is so constructed that forcing of the lock into position will frictionally lock the same.

An important object of the invention is to provide an improved repair lock adapted to be forced into a recess formed in the casting to be repaired or reinforced, the lock having novel means for expanding the same into engagement with the walls of the recess when forced under pressure into said recess, whereby said lock is frictionally wedged within the recess.

A particular object of the invention is to provide an improved cold flow lock, of the character described, having novel means associated with its lower portion adapted to coact with the bottom of the recess upon the application of downward pressure, whereby said lower portion will flow or be distorted laterally into engagement with the longitudinal walls of said recess to positively wedge or clamp the lock within the recess.

Another object of the invention is to provide an improved cold flow lock having a base portion adapted to engage and coact with the bottom of the recess so as to distort or expand the longitudinal lower margins of the lock into friction engagement with the side walls of said recess, thereby preventing displacement of said lock.

A further object of the invention is to provide an improved repair lock which may be formed in one or more sections and preferably an upper ductile section and a lower or expanding base section of relatively hard metal, the lower section distorting or expanding the upper section into frictional engagement with the walls of the recess when said upper section is forced into said recess and tending to securely lock the sections to each other so as to increase the strength thereof; a lock of this type having been found to be highly desirable in repairing or reinforcing ill-designed castings or castings having a multiplicity of or contiguous openings.

Still another object of the invention is to provide an improved cold flow lock which includes an upper portion of ductile or distortable metal and a lower base portion of relatively hard or undistortable metal, the lower portion acting as a wedge or expander to spread or cause the upper portion to flow laterally into frictional engagement with the side walls of the recess when pres-

2

sure is exerted against said upper portion to force the same into said recess; there being coacting means associated with the portions of the lock to fasten the same together when said lock is in locking position.

A construction designed to carry out the invention will be hereinafter described together with other features of the invention.

The invention will be more readily understood 10 from a reading of the following specification and by reference to the accompanying drawings, wherein an example of the invention is shown, and wherein:

Figure 1 is an isometric view of a two-piece 15 form of lock.

Figure 2 is a longitudinal, vertical, sectional view of a portion of the lock.

Figure 3 is a plan view of the lock.

Figure 4 is a transverse, vertical, sectional 20 view, taken on the line 4—4 of Figure 2.

Figure 5 is an isometric view of another two-piece lock.

Figure 6 is an end elevation of the two-piece 25 lock inserted in a recess.

Figure 7 is a view, similar to Figure 6, showing a slight modification.

Figure 8 is an underside isometric view of the 30 upper portion of the lock shown in Figure 6 with grooves formed therein.

Figure 9 is a transverse, vertical, sectional 35 view of this lock inserted in a recess, and

Figure 10 is a longitudinal, vertical, sectional 40 view taken on the line 10—10 of Figure 9.

In the drawing, Figs. 1 to 4, inclusive, the 45 numeral 30 designates a two-piece locking member which includes an upper section 31 of ductile metal such as Invar or other metal which becomes hardened upon being worked, and a lower section 32 of relatively-hard metal. The upper section preferably consists of a plurality of upright, cylindrical portions 33 disposed in the same horizontal plane and having their axes aligned. Intermediate, vertical web-portions 34 interconnect the adjacent cylindrical portions 33, whereby the upper section 31 has undulating, longitudinal side walls. Although the lower section 32 may be made in one piece, it is preferable to form the same of a plurality of conical-shaped wedges 35 having the same diameter as the cylindrical portions 33 of the upper section. A rectangular lug 36 extends diametrically across the upper, flat surface of each wedge 35, terminating short of the periphery thereof as shown in Figures 2 and 4, and adapted to engage within a complementary groove or recess 37 formed in the

lower surface of each cylindrical portion 33. The recesses 37 extend transversely of the upper section 31 and each recess has inclined or beveled side and end walls. The side and end walls of each lug 36 are also inclined or tapered. To assure expanding or deforming of the upper section 31 upon insertion of the same within a recess in a casting, the cross-sectional area of each lug 36 is slightly greater than the cross-sectional area of its respective recess. Thus, the lugs will not readily fit within the recesses and must be forced thereinto.

In using a locking member of this construction, a recess 38 substantially complementary to the locking member 30 is formed in the casting 39 to be repaired or reinforced. The wedges 35 are placed within the recess 38 with their lugs 36 extending transversely thereof and the upper section 31 is inserted on top of said wedges so that the recesses 37 are aligned with said lugs. The upper section is then forced downwardly, by applying pressure to the upper surface thereof, until said upper surface is substantially flush with the exterior of the casting being repaired or reinforced. Due to the ductility of the upper section, the downward pressure exerted upon the same will cause the metal surrounding the recesses 37 to flow outwardly into engagement with the side walls of the recess 38, thereby enlarging said recesses 37 and permitting the lugs 36 to completely enter and fill the same. Of course, the radial expansion or flowing of the lower portion of the section 31 is aided by the wedging action of the inclined walls of the lugs and recesses. Also, the distortion of the lower portion of the section 31 will result in a general radial distortion of each cylindrical portion 33 so as to bring about a wedging action between said sections and the adjacent surfaces of the recess 38. Thus, the upper section 31 will be firmly wedged within the recess and frictionally secured to the wedges 35.

In Figures 5 and 6, a locking member 40 is shown. The member 40 is constructed of ductile metal and has a single, inverted, V-shaped groove or channel 41 extending longitudinally throughout the length of its lower surface. A wedge member 42, triangular in cross-section and of substantially the same width and length as the member 40, is adapted to engage within the groove 41. Both the groove and wedge are of greater width than depth or thickness, whereby their inclined surfaces have only a slight pitch. However, the inclination of the pitch of the walls of the groove 41 is slightly greater than that of the inclined surfaces of the wedge member 42, whereby when the locking member and wedge are inserted within a recess said wedge will have a tendency to enlarge or spread said groove. To increase the spreading action of the wedge, both lower, longitudinal, marginal edge portions thereof are arced or beveled as shown at 43.

A recess 44, complementary to the locking member 40, is cut or otherwise formed in the casting 45 to be repaired or reinforced and the wedge 42 is placed in the recess with its base engaging the bottom thereof. The member 40 is then inserted into the recess and forced downwardly, by hammering or other suitable means, until its upper surface is flush with the exterior of the casting 45. Due to the beveled surfaces 43 of the wedge and the greater pitch of the walls of the groove 41, it is obvious that by forcing the member 40 downwardly said groove will be spread so as to be fully engaged by said wedge and the lateral surfaces of said member 40 will be wedged

into frictional engagement with the side walls of the recess 44. Although it is preferable for the wedge and groove to be triangular in cross-section, their adjacent surfaces may be arced or curved as shown at 48 and 49 in Figure 7 with the arc or curvature of the wedge surface 49 being greater than the arc or curvature of the groove surface 48 so as to facilitate expansion or deforming of the locking member 40.

In Figures 8 to 10, a locking member 50 substantially identical to the locking member 40 and having semi-cylindrical protuberances 51 formed on its side walls is shown. A longitudinal groove or channel 51, arced or curved in cross-section similar to the groove 48 shown in Figure 7, is formed in the lower surface of the member 50 and is adapted to be engaged by the substantially complementary curved or arced upper surface of a wedge or wedge member 52. The upper surface of both longitudinal, marginal edge portions of the wedge 52 is beveled as shown at 53 in the same manner as the beveled surfaces 43 of the wedge 42. A plurality of rectangular lugs 54 are formed on the upper arced surface of the wedge 52, extending transversely at a right angle to said wedge and being spaced longitudinally throughout the length thereof. The end walls of each lug 54 are preferably perpendicular, while the side walls are inclined and converge upwardly toward each other as shown in Figure 10.

Substantially complementary recesses 55 for receiving the lugs 54 are formed transversely in the curved surface of the groove 51 and are disposed so as to be aligned with the external semi-cylindrical protuberances 51 of the member 50. The end walls of each recess 55 are preferably perpendicular, while the side walls are inclined and converge toward each other at the bottom of said recess. However, any or all of the walls of the lugs and recesses 55 may be perpendicular to provide maximum shear or tapered to assure expansion of the lock. In order to assure locking of the member 50 to the wedge 52 when the same are inserted within the recess 55 of a casting 59, the lugs 54 are of slightly greater width than the recesses 55.

In using this form of the locking member, the wedge 52 is first inserted within the casting recess 55 and then said locking member is forced downwardly until the upper surface thereof is flush with the exterior of the casting 59, or said wedge may be partially wedged within the member prior to insertion thereof in said recess. The lower portion of the member 50 is expanded or deformed outwardly by the curved or arced upper surface of the wedge 52, this spreading action being assisted by the beveled surfaces 53 of said wedge. Although the lugs 54 and recesses 55 assist in the spreading and wedging of the locking member within the recess 55, the same function primarily to frictionally fasten said member to said wedge. Manifestly, the member 50 is expanded and its semi-cylindrical protuberances 51 firmly engage the complementary side walls of the recess 55 in the same manner as the member 40 and its semi-cylindrical protuberances 47 engage the side walls of its recess 44. In fact, the locking member 50 is identical to the locking member shown in Figure 7, with the exception of the coacting lugs and recesses, and the contiguous surfaces of the groove 51 and wedge 52 may, if desired, be angular instead of curved or arced.

Of course, the invention may be carried out in various ways which are not illustrated, since the

purpose of the invention is to expand or deform the lower portion of the locking member into firm, frictional engagement with the side walls of the recess formed in the casting to be repaired or reinforced. As has been illustrated, the locking member may be deformed in different ways however, it is pointed out that whereas in my former Patent No. 2,321,629, I employed a thin vertical wedge which extended into the upper portion of the ductile element, the present invention involves a transversely broadened or flattened wedge member which engages only the lower portion of the ductile member and has an improved and different action. In my former patent the wedging action continued into the upper portion of the ductile element making it difficult to control the compression stresses and limited the possibility of cool working which is inculcated in the present improvement which has the advantage of wedging the bottom of the element while leaving the upper portion free for cold flowing and cold working. Further, by confining the wedging action to the lower portion of the ductile element the cross-sectional area of the major portion of said element is strengthened. By making the wedge element broad, the amplitude of the spread is increased and the spread is confined to the portion where it is most effective. As has been herein-before fully set forth, the wedge or wedges may be locked to the upper section by means of coacting lugs and recesses. Manifestly, the herein-before described locking members may be used to repair and reinforce forgings and metallic members other than castings.

The foregoing description of the invention is explanatory thereof and various changes in the size, shape and materials as well as in the details of the illustrated construction may be made, within the scope of the appended claims, without departing from the spirit of the invention.

What I claim and desire to secure by Letters Patent is:

1. In combination with a casting, a reinforcing member adapted to be inserted at a point of stress including, an elongate integral element positioned within a recess formed in the casting with its longitudinal axis parallel to the surface of the casting, the element being formed of ductile metal and having transverse recesses formed in its lower surface, wedge means of relatively-hard metal bearing against the bottom of the casting recess for expanding said element into snug engagement with the walls of said casting recess, and lugs formed on the upper surface of the wedge means adapted to engage within the element recesses to frictionally lock said means to the element.
- 15 2. In combination with a casting, a reinforcing member adapted to be inserted at a point of stress including, an elongate integral element positioned within a recess formed in the casting with its longitudinal axis parallel to the surface of the casting, wedge means engaging and bearing against the bottom of the recess for deforming and expanding the element into snug engagement with the walls of said recess, said element having recesses formed in its lower surface, and lugs formed on the upper surface of the wedge means adapted to engage within the element recesses to frictionally lock said wedge means to the element.
